UNITED STATES PATENT OFFICE.

WILLIAM ANSELM COATES, OF CHORLTON-CUM-HARDY, AND DAVID REGINALD DAVIES, OF STRETFORD, ENGLAND, ASSIGNEES TO WESTINGHOUSE ELECTRIC AND MANUFACTURING COMPANY, A CORPORATION OF PENNSYLVANIA.

ELECTRICAL SWITCH GEAR.

Application filed September 2, 1921, Serial No. 497,902, and in Great Britain September 28, 1920.

Our invention relates to electrical switch gear and particularly to switch gear of the enclosed type.

One object of our invention is to provide a switch gear in which various parts thereof, such as the isolating and selector switches, the numerous electrical conductors, the instrument and other transformers or such of these devices as are or may be connected to the main oil switch and the bus bars, are enclosed in casings, usually of metal.

A further object of our invention is to provide switch gear of the above type wherein the switches for connecting the oil switch to the cable leads or bus bars are disposed in an oil tank with their movable contacts adapted to be operated by bodily raising and lowering the tank.

Another object of our invention is to provide a switch mechanism wherein selector switches are provided for selectively connecting the main or oil switch with either of two sets of bus bars and wherein the selector switches are of the bridge type having movable bridges disposed within an oil tank and adapted to be moved into registry with selected contacts of the selector switches.

Another object of our invention is to provide a switch mechanism having the above characteristics wherein the bridge members of the selector switches are mounted within an oil receptacle and are operated by bodily raising and lowering the receptacle, and wherein movement of the tank for operation of the bridges is precluded so long as the bridges are in an intermediate position between open and closed positions and wherein in selective movement of the bridges is precluded so long as the switch is in closed position.

A further object of our invention is to provide a switch mechanism, of the above-described character, wherein the tank for enclosing the isolating and selector switches is moved bodily for the purpose of opening and closing the switches and wherein movable supporting members for operating the tank are simultaneously actuated by a single operating device disposed to be conveniently accessible from the front of the mechanism.

These and other objects that will be made

apparent throughout the further description of the invention are attained by means of the switch mechanism hereinafter described, and illustrated in the accompanying drawings.

According to our invention, the isolating and also the selector switches, if provided, are arranged in an oil tank and are operated by bodily raising and lowering the said tank. The switches are conveniently of the bridge type having the contact fingers downwardly directed, the bridges of the switches being supported in the bottom of the tank on suitable insulators and in such position relative to the contact fingers that the switches are closed when the tank is raised and are opened when the tank is lowered.

The tank containing the isolating and selector switches may be raised and lowered for closing and opening the said switches by any convenient means, such, for example, as screw-and-nut mechanism operated by turning a handle through a chain and sprockets.

In cases where duplicate sets of bus bars are provided with selector switches for connecting up either the one or the other set of bus bars, the bridges of such selector switches may be so disposed in the tank that they may be moved horizontally to bridge alternative sets of contact fingers connected, respectively, to the two sets of bus bars, any suitable mechanism being employed for shifting the bridges.

In a convenient constructional embodiment of the switch gear, the main oil switch tank and the isolating and selector-switch tank may be located, the one behind the other, a tank containing the series transformers and certain of the electrical conductors being disposed across the top of both tanks while the cable-dividing or trifurcating box may be located between them. The bus bar chamber may be located above the rear portion of the isolating and selector-switch tank.

To enable the invention to be clearly understood, it will now be described with reference to the accompanying drawings, which illustrate, by way of example, a construction of switch gear in accordance with the distribution system having split-conductor protection.

Figure 1 is a side elevation of a complete switch gear embodying our invention;

Fig. 2 is a front elevation of the switch gear;

5 Fig. 3 is a sectional view showing the essential elements of one phase of the switch gear, the section being taken on the line III—III of Fig. 2;

10 Fig. 4 is a sectional elevation of the switch gear looking in the direction of the arrow, (Fig. 3), the left-hand portion being a section on the line IV—IV while the right-hand portion is a section on the line V—V; and

15 Fig. 5 is an electrical diagram of the circuits of one phase conductor of the switch gear, and

20 Fig. 6 is a horizontal sectional view taken on the line VI—VI of Fig. 4, in the direction of the arrows.

Referring first to Fig. 5, which shows, in respect of one phase conductor, the connections which the switch gear is designed to control. 1 is the cable, for example, an incoming three-core split-conductor feeder and 2 and 3 are, respectively, the sets of main and auxiliary or "hospital" bus bars, to which the cable 1 is to be alternatively connected.

30 The split conductors 4 of each phase conductor core 5 are connected to the terminals 6 of the isolating switches 7 which are of the bridge type, the bridges thereof being indicated at 8. The other terminals 9 of these switches are connected, by means of conductors 11 and 12, to the split-conductor-protection transformer 13 and the instrument transformer 14 or such of these devices as are provided and, thence, by means of conductors 15 and 16, to one pole 17 of the main oil switch 18. The other pole 19 of the oil switch is connected, by a conductor 20, to the two fixed contacts 21 of the selector switches 22 and 23, the bridge of which is indicated at 24. The other fixed contacts 25 and 26 of the selector switches 22 and 23, respectively, are connected to the main bus bars 2 and the hospital bus bars 3, respectively, by conductors 27. The switches 22 and 23 are adapted to be closed alternatively according to which set of bus bars it is required to use.

Referring now to Figs. 1 to 4, the cable 1 is sealed into a trifurcating or dividing box 30 (see Fig. 1), which is attached to a hollow member 31, through which the cores 5 extend and in which the conductors 4 separate, the latter being connected to the terminals 6 of the isolating switches 7, which are mounted, with their contact fingers downwardly directed, in a table 32 supported by the frame-work 33 of the switch gear. The transformers 13 and 14 and the connections between these devices and the isolating and selector switches and the oil switch 18

are arranged in a casing 34 which extends horizontally across the frame-work of the switch gear, as clearly shown in Figs. 1 and 3.

The head 35 of the oil switch 18 is attached, by set screws or any other convenient means, to the frame-work 33 beneath the front end of the casing 34, as shown in Fig. 3. The casing 34, when the connections therein have been made, is adapted to be filled with a compound and is provided with removable plugs 36 to permit the compound to be poured in after the casing has been secured in position.

The fixed contacts 21, 25 and 26 of the selector switches are mounted on the table 32 and depend therefrom in a manner similar to the fixed contacts 7 of the isolating switches, and the fixed contacts 25 and 26 are respectively connected, by means of the strip conductors 27, to the bus bars which are located in a metal chamber 37, situated behind the casing 34 at the rear of the switch gear and supported on the framework 33 above the selector switches.

The depending fixed contacts of the isolating and selector switches are provided with insulators 39, a partition 40 (Figs. 3 and 4) being located between the pairs of poles of each switch. The bridges 8 of the isolating switches are carried on rods 8¹ mounted on a casting or frame 41, which is of skeleton form and extends up at the corners, where it is provided with lugs 46, to which the oil tank 42 is attached. The bridges 8 are insulated from the rods 8¹ by insulating sleeves 8².

The bridges 24 of the selector switches are carried, in a similar manner to the bridges 8, on rods 53 from which they are insulated by sleeves 53¹, said rods being attached to, and supported by, brackets 57, adapted to slide on rods 54, secured in the frame 41. The bridges may, therefore, be shifted to and fro along the floor of the tank 42, from the position indicated in full lines, in the direction of the arrow into the dotted-line position, as shown in Fig. 4. When the said bridges 24 are in the left-hand (full-line) position, they will effect engagement of the selector-switch contacts 21 with the contacts 25, by which the bus bars 2 are connected. When the said bridges are in the right-hand (dotted-line) position, they will effect engagement of the selector-switch contacts 21 with the contacts 26 so that the bus bars 3 are connected.

Any suitable device may be provided for shifting the bridge 24 from one position to the other for selectively connecting the bus bars. As shown, for example, a vertical shaft 55 has a forked lever 56 at its lower end which engages one of the brackets 57. The shaft 55 has a squared upper end 58 on which a link 59 is mounted, said link being

operatively connected to a bevel gear wheel 60 in mesh with a bevel gear wheel 61 on the end of the shaft 62. The shaft 62 extends through the shaft 51, which is made hollow 5 for that purpose, and is furnished with an operating handle 63.

Rotation of the shaft 55 will move the lever 56 to and fro and so cause the brackets 57, with the rods 53 and bridge pieces 24, 10 to slide along the rods 54 to occupy one or another of the desired positions. The squared portion 58 of the shaft 55 slides freely in a square hole in the link 59 to permit the tank 42 to be moved up and down, as will now be 15 described.

The tank 42 is adapted to be raised and lowered in order to close or open the isolating and selector switches by engagement of the bridge portions 8 and 24 with the corresponding contact fingers 7, 21, 25 and 26. For this purpose, the tank 42 is supported at each corner by means of a screw 43 rotatably mounted in the framework 33 and provided with a head 44 provided with sprocket 23 teeth or to which is attached a sprocket wheel 45.

The screws 43 are in operative engagement with screw-threaded orifices in the lugs 46 to which are secured the upper corners of the 20 tank 42. With this construction, it will be seen that, by rotating the screws 43 in the one or the other direction, the tank may be bodily raised or lowered to close and open the isolating and selector switches.

35 The sprocket wheels 45 may be simultaneously rotated by means of a single sprocket chain, such as a cycle chain 47, (Fig. 1), which passes around all the sprocket wheels 45. The casing 31 is provided in the middle 40 with a tunnel 31^a (see Figs. 1 and 3) through which the chain 47 passes. One of the sprocket wheels 45 is conveniently provided with a bevel gear wheel 49, which is engaged by another bevel gear wheel 50, connected 45 to the hollow shaft 51, which is extended to the front of the apparatus where it is provided with a hand wheel 52, an indicator (not shown) being preferably provided to show whether the isolating and selector 50 switches are open or closed.

To prevent movement of the tank when the bridges 24 are in an intermediate position and to prevent movement of the bridges 24 when the tank is in its upper position 55 and the isolating and selector switches are closed, the following interlock mechanism may be employed. A rod 64, depending from the table 32, is adapted to engage the lever 56 when the bridges 24 are in an intermediate position and thereby prevent the tank being raised. When the tank is in its upper position, the rod 64 is on the one or the other side of the lever 56 to prevent movement of the same to shift the position 60 of the bridges when the switches are closed.

A convenient position for the potential transformer 65 (Fig. 5), when provided, is on the top of the casing 34, the position of the transformer tank being indicated at 66 by dotted lines. The transformer fuses will 70 be preferably located in the tank 66 and immersed in the oil therein. The various casings and other parts of the switch gear are diagrammatically indicated by means of broken lines in Fig. 5. In some cases, instead of arranging the series transformers 13 and 14 in a separate casing 34, it may be found convenient to mount these devices in the oil tank 42 of the isolating and selector switches, in which case, the bridge or bridges 80 for normally connecting between the incoming cable and the said transformers may be divided, and the latter devices be connected between the divided bridge or bridges.

The terminals of the isolating and selector 85 switches are preferably encased in tubes 67 of insulating material, such as micanite, and are connected to the transformer devices and the oil switch by copper-strip conductors. The bus bars 2 and 3 are advantageously 90 formed of strip conductors and the bus bar chamber 37 is preferably rectangular in cross section and formed of cast or rolled-metal sections joined together to form a tube. Interlocking mechanism, which may conveniently be located in a housing 69, is preferably provided in order (1) to prevent the opening of the isolating and selector switches when the oil switch is closed, (2) to prevent the closure of the oil switch when the isolating and selector switches are closed, (3) to 95 prevent the closure of the isolating and selector switches when the oil switch is closed and (4) to prevent the removal of some or all of the various casings or receptacles, except under safe conditions. As various kinds of such interlocking mechanism are well known, a complete description thereof is deemed unnecessary. The tank for the oil switch 18 and the tank 42 are filled with oil 100 to the desired level, the bus bar chamber 37 and the trifurcating box 30 and casing 31 are filled with solid insulating compound and the casing 34 may also be filled with a compound.

110 It will be understood that the invention is not limited to the particular arrangement of switch gear illustrated, as this may be modified in various ways; for example, the bus bar chamber 37 and the casings 34, the oil switch 18, the isolating and selector-switch tank 42 and the trifurcating box 30 may be arranged in different positions relatively to one another. In some cases, the bus bars 115 may not be provided in duplicate so that certain of the so-called selector switches 22 and 23 may be omitted, in which case the said switches would more properly be termed isolating switches. It will further be understood that the invention is equally ap- 120 125 130

plicable to other systems of electrical distribution than the three-phase system herein described.

The term "iron-clad" is not to be understood as limiting the invention to the use of iron casings as, in some cases, for example, in switch gear for heavy currents, a non-magnetic metal may be preferable.

We claim as our invention:—

10. Switch mechanism comprising a closure member, a receptacle movably supported thereon and closed thereby, a switch member mounted on the closure member and extending into the receptacle, a switch member within the receptacle and movable therewith, and means for moving the receptacle with respect to the closure member for moving the last-mentioned switch member into and out of engagement with the first-mentioned switch member.
15. Switch mechanism comprising a receptacle, a switch member within the receptacle, a supporting structure for the receptacle, a plurality of switch members mounted thereon, means for relatively moving the receptacle and the supporting structure for operatively connecting the said members, and means for moving one of the switch members for selectively engaging other of the said members.
20. Switch mechanism comprising a receptacle, a switch member within the receptacle, a supporting structure for the receptacle, switch contact members mounted thereon, means mounted on the supporting structure for relatively moving the receptacle and the supporting structure for operatively connecting the contact members and the switch member, and means mounted on the supporting structure for moving the switch member for selectively engaging the said contact members.
25. Switch mechanism comprising a supporting structure, a movable receptacle sup-

ported thereon, switch contact members 45 mounted upon the supporting structure and extending into the receptacle, a switch member slidably mounted within the receptacle and movable therewith, means mounted on the supporting structure for selectively moving the switch member into registry with selected contact members and means for moving the switch member into engagement with the selected contact members.

5. Switch mechanism comprising a supporting structure, a movable receptacle supported thereon, switch contact members mounted upon the supporting structure and extending into the receptacle, a switch member slidably mounted within the receptacle 60 and movable therewith, means mounted on the supporting structure for selectively moving the switch members, means for moving the switch members into engagement with the selected switch members, and means for preventing selective movement of the switch member so long as the said switch member is in operative engagement with a contact member.

6. Switch mechanism comprising a supporting structure, a movable receptacle supported thereon, switch contact members mounted upon the supporting structure and extending into the receptacle, a switch member slidably mounted within the receptacle 75 and movable therewith, means mounted on the supporting structure for selectively moving the switch members, means for moving the switch members into engagement with the selected switch members, and means for 80 preventing movement of the switch member toward engaging position except when it is in registry with the contact member.

In testimony whereof, we have hereunto subscribed our names this sixteenth day of August, 1926.

WILLIAM ANSELM COATES.
DAVID REGINALD DAVIES.
